[57] CLAIM

The ornamental design for a work desk for a word processor unit, as shown and described.

DESCRIPTION

FIG. 1 is a perspective view of a work desk for a word processor unit embodying our new design;

FIG. 2 is a front elevational view thereof;

FIG. 3 is a side elevational view thereof, the opposite side being a mirror image;

FIG. 4 is a rear elevational view thereof;

FIG. 5 is a top plan view thereof;

FIG. 6 is a perspective view of a first modification of our new design;

FIG. 7 is a front elevational view of the modification of FIG. 6, the side elevations of the first modification being the same as shown in FIG. 3;

FIG. 8 is a rear elevational view of the first modification of FIG. 6;

FIG. 9 is a top plan view of the first modification shown in FIG. 6;

FIG. 10 is a perspective view of a second modification of our new design;

FIG. 11 is a front elevational view of the modification of FIG. 10, the side elevations of the second modification being the same as shown in FIG. 3;

FIG. 12 is a rear elevational view of the second modification shown in FIG. 10; and

FIG. 13 is a top plan view of the second modification of FIG. 10.
